MANUALLY PORTABLE CRANKCASE DRAIN
PUMP ASSEMBLY

Albert J. Granberg, Oakland, Calif.

Application October 3, 1949, Serial No. 119,374

4 Claims. (Cl. 103—118)

1

My invention relates to the draining of liquids from containers, tanks and the like, and more particularly to a manually portable motor and pump assembly for draining the oil from the crankcases of automobiles, boats or the like.

Heretofore it has been the practice in changing the oil in the crankcase of automobiles, to run the auto over a pit or raise the same upon a rack, and then remove the drain plug to permit the old oil to drain out from the crankcase, following which the plug must be replaced and the crankcase then refilled with fresh oil through the filler pipe.

The present invention has for its main purpose to completely eliminate the necessity for such time-consuming operations and provide manually portable means enabling anyone, without the necessity of utilizing pits or racks, to drain the oil from such crankcase with a minimum of effort and time. This is accomplished by providing a very light motor-pump assembly adapted for manual portability and including a plurality of selectable suction tubes of different diameters to fit the dip stick openings of the various makes of automobile engines. Each of these tubes is attachable to the inlet of the pump and when so attached and inserted into the crankcase through the dip stick opening, functions as the suction line of the pump. The outlet end of the pump is provided with a flexible hose for discharging the pumped oil into a suitable drain or container.

For details of my invention in its preferred form, reference will be had to the accompanying drawings wherein—

Figure 1 is a view in section through a motor and pump assembly embodying the features of the present invention;

Figure 2 is an end view of such assembly with an end plate removed to expose the structural arrangement of the pump; and

Figure 3 is a detail of the coupling between the suction line tube and the pump.

The invention as illustrated comprises an electric motor 1, to the shaft of which is connected a pump 3 through a gear reduction train 5.

The motor is of light weight construction, having a rating of the order of $\frac{1}{4}$ horsepower, and is provided with the necessary ventilating features such as a fan 7 and vent openings 9. The front end of the motor casing is closed by a casting 11 which supports the front bearings 13 for the motor, and provides a housing for the gear train. Such casting is formed with a lateral extension 15 over the motor casing to constitute a suitable handle for carrying the assembly.

The pump is mounted on the front face of the casting and includes a housing 17 formed to provide a chamber 19 to receive the pump rotor 21 mounted on the pump shaft 23 which extends through suitable bearings into the casting, where it carries the large gear 25 of the gear reduction

2

train, such gear meshing with a pinion 27 on the front end of the motor shaft.

The rotor axis is disposed slightly off center with respect to the axis of the chamber in which it lies. At angularly spaced distances about the rotor, the rotor is formed with longitudinal recesses 29 adapted to each slidably receive a cylindrical roller 31, preferably of synthetic rubber. During operation of the pump, centrifugal force will cause these rollers to hug the inner surface of the rotor chamber and, due to the eccentric relationship between the axis of the rotor and the axis of the chamber, radial movement of the rollers will occur as the spacing between the rotor and the inner surface of the chamber varies. Movement of the rotor will cause a condition of reduced pressure at the inlet of the pump as the rollers move across the intake opening, thereby causing liquid to be taken into the pump from which the liquid will be forced out of the pump as the rollers approach and move across the pump outlet.

In connection with the operation of the pump described above, and more particularly with reference to the compression side of said pump, it is very desirable to implement the centrifugal force, in keeping the rollers in pressure engagement with the surface of the chamber to maintain the pump pressure at its maximum value. With this in mind, I provide a pressure groove 33 in the end wall of the chamber concentric with the circumference of the rotor and adapted to communicate with the roller recesses as they move along the groove. This groove begins at approximately the start of the pressure stroke and terminates in a bend 35 establishing communication with the outlet of the pump, whereby a roller approaching the landing on the pressure side of the pump will have its recess intercepted by the groove and establish communication with the outlet of the pump. Thus the pressure existing at the pump outlet will automatically be applied behind the roller as a positive force urging the roller into pressure engagement with the cylindrical wall of the pump chamber.

It is important at this point to note that the rollers, even if they begin to recede before they reach the termination of the landing on the pressure side of the pump, are not precluded or blocked in such movement because as the space or volume behind the roller tends to become smaller, the pressure therein will increase to a point where it will overcome the back pressure of the liquid on the discharge side of the pump and cause a momentary reverse flow and momentarily increase the pressure against the following roller.

As a roller, however, moves beyond communication with this pressure groove, and it begins to approach the landing on the low pressure side of the pump, relative inward radial movement of the roller in its associated recess becomes more pronounced, and the roller must be relieved of pres-

sure which would necessarily develop in the liquid which would then be trapped in the recess. To afford such relief, I provide another groove 37 in the end wall of the chamber concentric with the circumference of the rotor and adapted to intercept the roller recesses as they travel in their circular orbit. This relief groove begins at a point in line with the outlet of the pump and terminates in a bend 39 establishing communication with the inlet of the pump. Thus as the roller recess breaks connection with the pressure groove, it will establish connection with the relief groove whereby any liquid behind the roller may be discharged to the inlet of the pump by way of the passage offered by the relief groove.

The inlet and outlet of the pump are both internally threaded. The inlet end receives the female part 41 of a bayonet type coupling 43 having a pair of diametrically disposed pins 45 extending from the face thereof, while in the passage through the same there is provided an O ring 47 of resilient material.

The male portion 49 of the coupling is attached to the upper end of a tube 51 and is provided with an interrupted flange 53 for establishing a bayonet connection with the pins on the aforementioned female part, with the male end in sealing engagement with the O ring.

With the tube thus coupled to the inlet of the pump, such tube will act as a suction line, and when inserted into the dip stick opening of a crankcase, the motor may be started to pump out the oil from such crankcase through the discharge or outlet of the pump. A flexible hose 55 or the like coupled to the outlet of the pump can be used to direct the discharged liquid into any suitable container or drain. A plurality of suction line tubes of different diameters are contemplated, to adapt the motor-pump assembly for use with different engines.

The motor-pump assembly is of relatively light weight and the provision of a handle enables the same to be carried about manually with ease, and accordingly greatly simplifies the use thereof in the draining of the crankcases of automobiles or boats without the necessity of resorting to the use of pits or racks and with great savings in time and labor. By disposing the handle in the plane of the inlet, the use of the equipment for its intended purpose is made that much easier for the operator.

After a crankcase has been drained in the manner indicated, the same may then be filled with fresh oil, utilizing the same equipment, but this time, pumping the oil from a drum or container into the crankcase.

It will become apparent from the above description of my invention in its preferred form, that the same fulfills the purposes for which the invention has been developed, and while I have described the preferred embodiment in considerable detail, I do not desire to be limited in my protection to the same, except as may be necessitated by the appended claims.

I claim:

1. A manually portable drainer for draining an automobile crankcase or the like having a filler opening therein, comprising an electric motor having a shaft, a pump having a chamber with an inlet and an outlet connected thereto, and a rotor in said chamber having a shaft, means connecting said pump in driving connection to said motor to form a motor-pump assembly, said connecting means including a housing intermediate said pump and said motor and hav-

ing a handle lying in a plane substantially through said motor shaft and pump inlet, a gear train for said housing interconnecting said motor shaft and pump shaft, a bearing in said gear housing supporting the connected end of said motor shaft, a tube adapted to fit into such crankcase through such opening, and means for removably coupling said tube to said pump inlet.

2. A manually portable drainer for draining an automobile crankcase or the like through its filler opening, comprising an electric motor having an open-ended casing, including a bearing at one end for receiving and supporting one end of its rotor shaft, a gear housing closing the opposite end of said casing and having a bearing therein for receiving and supporting the other end of said rotor shaft, a handle integrally formed with said gear housing and extending laterally over said motor in a vertical plane substantially through the axis of said rotor shaft, a pump affixed to said gear housing and having a chamber with an inlet and an outlet connected to said chamber, a rotor disposed in said chamber, means connecting said pump rotor in driving connection to the shaft of said motor, said means involving a gear train in said gear housing and coupled at one end to said motor shaft and at its other end to said pump rotor, a tube adapted to fit into such crankcase through such filler opening, and means for removably coupling said tube to said pump inlet.

3. A gear drive and pump assembly for attachment to the open end of an electric motor casing, comprising a gear housing adapted at one end to close the open end of such motor casing and having an exposed bearing to receive and support the adjacent end of the rotor shaft of such motor, a pump mounted at the other end of said gear housing, and a gear train in said housing for drive connecting such rotor shaft to said pump, said pump having an inlet and an outlet, and a handle extending from said assembly in a plane passing substantially through said pump inlet and the axis of said pump rotor.

4. A gear drive and pump assembly for attachment to the open end of an electric motor casing, comprising a gear housing adapted at one end to close the open end of said casing and having an exposed bearing to receive and support the adjacent end of the rotor shaft of such motor, a pump mounted at the other end of said gear housing, and a gear train in said housing for drive connecting such rotor shaft to said pump, said pump having an inlet and an outlet, and a handle extending from said gear housing in a plane passing substantially through said pump inlet and the axis of said pump rotor.
